UNITED STATES PATENT OFFICE.

PAUL W. THOMAS, OF BROOKLYN, NEW YORK.

DOOR-HANGER.

1,106,992.

Specification of Letters Patent. Patented Aug. 11, 1914.

Application filed March 10, 1914. Serial No. 823,820.

To all whom it may concern:

Be it known that I, PAUL W. THOMAS, a citizen of the United States, residing at Brooklyn, in the county of Kings and State 5 of New York, have invented new and useful Improvements in Door-Hangers, of which the following is a specification.

This invention relates to door hangers and it consists in the novel features hereinafter 10 described and claimed.

An object of the invention is to provide a door hanger of simple and durable structure adapted to support a door, the said hanger having anti-friction elements whereby 15 the door may be readily moved from closed to open position and vice versa.

In the accompanying drawing:—Figure 1 is a side elevation of the upper portion of a door showing the same suspended from 20 the door hanger. Fig. 2 is an under view of the hanger with the door removed. Fig. 3 is a detailed sectional view of the hanger cut on the line 3—3 of Fig. 1. Fig. 4 is a perspective view of one of the blocks used 25 in the hanger.

The hanger includes a strip 1 which may be secured in any suitable manner to the frame of the door (not shown). The said strip 1 is approximately U-shaped in trans- 30 verse section and is provided at its sides with longitudinally disposed ball races 2. The side portions of the strip 1 at the ends thereof are inturned as at 3, best shown in Fig. 2 of the drawing. U-shaped clips 4 are applied at intervals to the strip 1 and the side portions of the said clips 4 bear 35 against the side portions of the strip 1 and restrain the same against spreading. Plates 5 are located opposite the inner surfaces of 40 the side portions of the strip 1 and are provided at intervals with openings which receive bearing balls 6. The plates 5 are provided at the sides of the openings which receive the balls 6 with inwardly disposed 45 lugs 7 which bear against the balls 5 and serve to hold the same in position in the openings in the plates 5. A yoke member 8 is located between the plates 5 and is ap- 50 proximately U-shaped in transverse section. The said yoke member is provided at its sides with ball races 9 which receive the inner side portions of the balls 6. The in- 55 turned ends 3 of the sides of the strip 1 project into the path of movement of the plates 5 and limit the movement of the said

plates with relation to the strip 1. Blocks 10 are carried at the end portions of the yoke member 8. The said blocks are approximately U-shaped in edge elevation as best indicated in Fig. 4 of the drawing and the end portions of the said blocks pass through the yoke member 8 and are secured together by means of filler blocks 11 which are suitably secured to the ends of the blocks 10 and which bear at their sides against the 60 inner surfaces of the side portions of the yoke member 8 and restrain the said side portions from bending in an inward direction. The blocks 10 are provided at their lower intermediate portions with slots 12 65 which open at one side of the blocks and the blocks at the open ends of the slots 10 are provided with upstanding lugs 13. Headed studs 14 are suitably secured to the edge of the door 15 and the intermediate 70 portions of the said studs are received in the slots 12 while the sides of the heads of the said studs bear against the lugs 13 and consequently the studs are restrained against 75 turning movement and the studs when in 80 position can not slip out of the slots 12 pro- provided in the blocks 10. Nuts 16 are screw threaded upon the intermediate portions of the studs 14 and are adapted to be engaged with the under surfaces of the blocks 10 as 85 best shown in Fig. 3 of the drawing whereby the studs 14 are held against vertical movement with relation to the blocks 10 and consequently when the parts are as- 90 sembled it is impossible for them to become 95 displaced with relation to each other.

From the above description taken in conjunction with the accompanying drawing it will be seen that when the parts are assem- 95 bled as shown the door 15 is supported by the studs 14 which engage the blocks 10 and the blocks in turn are supported by the yoke member 8 which rests against the inner por- 100 tions of the balls 6 which are mounted for movement in the races 2 of the strip 1. Con-sequently the door may be moved readily edgewise and the plates 5 may follow the movement of the door within the bounds prescribed between the inturned end 3 of the sides of the strip 1. Therefore it will 105 be seen that a door hanger of simple and durable structural arrangement is provided and that the hanger is provided with anti- friction elements which not only assist in supporting the weight of the door but mate- 110

rially reduce the friction when the door is moved from closed to open position and vice versa.

Having described the invention what is claimed is:—

1. A door hanger comprising a strip which is approximately U-shaped in transverse section and which is provided at its sides with ball races, U-shaped clips mounted upon the strip and having their side portions in contact with the side portions of the strip, plates located adjacent the inner surfaces of the side portions of the strip and provided with openings, balls located in the openings and received in the said ball races, a yoke member located between the plates and provided at its sides with ball races which receive the inner portions of the balls, blocks carried by the yoke member and a door connected with the blocks.
2. A door hanger comprising a strip provided with longitudinally disposed ball races, a yoke member located between the side portions of the strip and having longitudinally disposed ball races, balls received in the said races, plates having openings which receive the balls U-shaped blocks carried by the yoke member, filler blocks connected with the ends of the U-shaped blocks and bearing against the inner surfaces of the side portions of the yoke member and a door connected with the U-shaped blocks.

3. A door hanger comprising a strip provided with longitudinally disposed ball races, a yoke member located between the sides of the said strip and provided with longitudinally disposed ball races, bearing balls located in the said races, plates having openings which receive the balls U-shaped blocks carried by the yoke member and provided with slots, said blocks having at the ends of the slots upstanding lugs, headed studs received in the slots and having their heads bearing against the lugs and a door carried by the studs.

4. In combination with a door hanger, a yoke member, U-shaped blocks carried by the yoke member and provided with slots, said blocks having at the ends of their slots upstanding lugs, headed studs received in the slots, and the heads of the studs bearing against the lugs, nuts screw threaded upon the intermediate portions of the studs and adapted to bear against the under sides of the blocks, a door carried by the studs a strip receiving the yoke member, balls interposed between the strips and yoke member and plates having openings which receive the balls.

In testimony whereof I affix my signature in presence of two witnesses.

PAUL W. THOMAS.
